Patented Apr. 29, 1919.

UNITED STATES PATENT OFFICE.

BIAGIO FALCONIERI, OF OAKLAND, CALIFORNIA. ASSIGNOR OF ONE-HALF TO JOHN B. ARENA, OF OAKLAND, CALIFORNIA.

ORCHARD-HEATER.

1,302,025.

Specification of Letters Patent. Patented Apr. 29, 1919.

Application filed July 24, 1918. Serial No. 246,430.

To all whom it may concern:

Be it known that I, BIAGIO FALCONIERI, a subject of the King of Italy, and a resident of Oakland, county of Alameda, and State 5 of California, have invented a new and useful Orchard-Heater, of which the following is a specification.

This invention relates to devices for heating the air in orchards, fields, or gardens to 10 raise the temperature in cold weather for the protection of the trees or plants from frost.

An object of the invention is to provide an effective and inexpensive device for burning crude petroleum or any of its low-grade 15 distillates in which complete combustion of the fuel is effected.

Another object of the invention is to provide an orchard heater which will operate to 20 produce complete combustion of the fuel regardless of the level of the fuel in the fuel chamber.

A further object of the invention is to provide an orchard heater which may be filled with oil and left exposed in all kinds 25 of weather without danger of rain getting into the oil chamber and putting the device out of service.

The invention possesses other advantageous features some of which, with the foregoing, will be set forth at length in the following description where I shall outline in full, that form of the invention which I have selected for illustration in the drawings accompanying and forming part of this specification. It is to be understood that I do not limit myself to the showing made by the drawings and description since I may adopt many variations of the preferred form within the scope of my invention as set forth in 40 the succeeding claims.

Referring to said drawings:

Figure 1 is a vertical section of the apparatus of my invention, a portion thereof being broken away to reduce the size of the 45 figure.

Fig. 2 is a vertical section of the lower portion of a modified form of heater of my invention.

The apparatus of my invention comprises 50 a receptacle or pot 2 in which the liquid fuel is placed. The pot is covered with a conical hood 3 on which is mounted a flue or stack 4 for producing the necessary draft to induce a sufficient amount of air into the heater to 55 complete combustion of the fuel. Air for

the initial combustion of the fuel is admitted into the pot through apertures in the hood 3. These apertures are preferably surrounded by funnels 5 either extending inwardly or outwardly from the hood and having their 60 smaller diameter at the discharge end so that the air entering the pot is given a directional movement toward the bottom of the pot. By this means the incoming air or a portion of it strikes the upper surface of the 65 fuel regardless of the amount of fuel in the pot and causes a very satisfactory initial combustion of the fuel. The axes of the funnels 5 preferably intersect the bottom of the pot at its center so that the incoming air 70 streams while directed toward the center of the pot will not interfere with each other. Each funnel or port 5 is provided on the outside with a gate 6 which is movable to control the amount of air which may pass 75 through the funnel. When the fire is first started these gates are only partially open, but as the heater becomes warm the gates are fully opened to permit the maximum amount 80 of air to enter the pot.

The stack 4 is sufficiently high to produce considerable draft through the hood, and the hood is rather shallow so that the flames, gases of combustion and incompletely burned mixture pass very rapidly into the 85 stack. This produces a zone of maximum temperature at the base of the stack and I introduce auxiliary air into the stack at this point to complete the combustion of the incompletely burned mixture. Formed in the 90 base of the stack is a row of apertures 7 through which air enters the stack at the zone of maximum temperature. Disposed within the stack in front of the apertures 7 and supported by the flange 8 is an annular 95 baffle wall 9 which causes the incoming air to be deflected upwardly into the stack. The area of the passage through the annular wall 9 is less than the cross-sectional area of the stack and consequently the speed of the 100 gases and incompletely burned mixture through the annular wall 9 is increased, thereby causing a large amount of air to be induced into the stack through the apertures 7. The air mixes with the incompletely burned mixture immediately above the baffle wall and causes the complete combustion of the mixture. The wall also produces eddy currents in the stack which produce a thorough mixture of the incoming air with the 110

incompletely burned gases. The shoulder 8 and annular wall 9 are preferably formed integral with the hood 3. A shield 12 arranged above the stack operates to deflect 5 the heated products outwardly and prevents them from ascending into the atmosphere directly.

In the modification shown in Fig. 2 the stack is mounted on and separated from the 10 hood by an upwardly diverging perforated member 13 through which air passes into the stack. The lower portion of the stack depends below the upper edge of the member 13 and forms therewith a passage of gradually 15 decreasing area upward. The zone of maximum temperature occurs adjacent the lower row of apertures in the member 13 and the greatest amount of air should be admitted into the zone. By forming the air 20 passage of gradually decreasing area upward, the amount of air entering the member through the succeeding rows of apertures is gradually lessened. The lower extension 25 of the stack besides operating to control the flow of air through the apertures also operates as a shield to prevent rain from entering the pot through these apertures. When it is desirable, a row of small apertures may be formed in the member 13 below 30 the larger apertures so that a limited amount of air may be introduced at those small apertures. By the construction shown in Fig. 2, air in gradually lessening amount is introduced into the ascending column of

burning mixture so that complete combustion of the fuel is assured. 35

I claim:

1. An orchard heater comprising a liquid fuel containing receptacle having a close fitting hood provided with a combustion 40 stack, and an imperforate conical funnel arranged on said hood and opening into the receptacle above the level of the liquid fuel therein and disposed with its axis intersecting the bottom of the receptacle, the inner 45 end of the funnel being of less diameter than the stack whereby the draft up the stack produces a draft through the funnel and against the surface of the fuel.

2. An orchard heater comprising a pot 50 adapted to contain liquid fuel, a conical hood on said pot provided with air inlet apertures, a stack mounted on said hood provided adjacent its base with a plurality of air inlet apertures, and an imperforate annular baffle wall within the stack and spaced therefrom opposite the apertures therein, and having its upper edge terminating in a plane substantially coincident with the top 55 of said apertures. 60

In testimony whereof, I have hereunto set my hand at Oakland, California, this 29th day of June 1918.

BIAGIO FALCONIERI.

In presence of—

FLOY CRANE,
J. B. GARDNER.
